ABSTRACT

A high-frequency heating apparatus, in which the high-frequency energy is uniformly distributed in a heating chamber for effectively heating the matter in the heating chamber. An energy distribution modifying means is provided in conformity to the shape of the heating chamber and on at least one of coaxial inner and outer conductors defining a cylindrical passage, which communicates with a waveguide coupled to a high-frequency oscillator. The high-frequency energy from the high-frequency oscillator is guided through the waveguide and the cylindrical passage to enter the heating chamber and is uniformly distributed in the heating chamber through the energy distribution modifying means.

FIG. 10

HIGH-FREQUENCY HEATING APPARATUS

This invention relates to a high-frequency heating apparatus.

In the usual high-frequency heating apparatus, the energy distribution in the heating chamber extremely lacks in uniformity between part of the chamber adjacent to the sidewalls thereof and the part adjacent the corners thereof.

Accordingly, an object of the invention is to provide a high-frequency heating apparatus capable of achieving a uniform energy distribution throughout the heating chamber for effectively heating the matter therein.

Another object of the invention is to provide a high-frequency heating apparatus having an energy distribution correcting means to obviate the nonuniformity of energy distribution in the heating chamber.

The invention will now be described in connection with a preferred embodiment thereof with reference to the accompanying drawings, in which:

FIG. 1 is a perspective view, partly broken away, showing a high-frequency heating apparatus, with a top cover removed, embodying the invention;

FIG. 2 is a fragmentary sectional view, to an enlarged scale, showing in detail an inner and outer conductor of a coaxial guide in the apparatus of FIG. 1;

FIGS. 3 to 5 show respective layouts of the heating chamber as well as respective energy distribution correcting means conforming to the shape of the heating chamber in the high-frequency heating apparatus according to the invention; and

FIGS. 6 to 10 are fragmentary perspective views showing examples of the energy distribution correcting means according to the invention.

Referring to FIGS. 1 and 2, a high-frequency heating apparatus according to the invention is shown having a heating chamber defined by top and bottom chamber walls 2 and 3, a front door 4 as well as by side and rear chamber walls (not indicated). The door 4 of the heating chamber 1 is hinged by hinges 5 to a support base and carries a door handle 6 to open and close it. The heating chamber 1 is electromagnetically isolated from the outside when the door 4 is closed. Outside the heating chamber 1 is disposed a rectangular or boxlike waveguide 7 secured by means of bolts 8 and nuts 9 to the top chamber wall 2 of the heating chamber 1. The waveguide 7 extends rearwardly of the heating chamber 1, and it is coupled to a high-frequency oscillator 10 disposed underneath its rear portion and having a radiating antenna extending within the waveguide 7. The waveguide 7 communicates with a cylindrical passage formed by a hollow cylindrical outer conductor 12 and a coaxial inner conductor 17. The outer conductor 12 is disposed centrally on the top of the heating chamber 1 and penetrates both the top wall of the heating chamber 1 and bottom wall of the waveguide 7. It is formed at its upper end with a flange 13, which is secured by means of welding to the waveguide 7, and at its lower end with lower extensions 14 radially spaced to correspond to the corners of the heating chamber 1, as is most clearly shown in FIG. 2. The extensions 14 constitute an energy distribution correcting means to provide uniform energy distribution in the heating chamber 1. The inner conductor 17 is secured to the lower end of a drive shaft 15 of an insulating material such as polypropylene penetrating the top wall of the waveguide 7 and leading to a motor 16 suitably mounted on top of the waveguide 7. The upper end of the inner conductor 17 is located within the waveguide 7, and the lower end thereof is located within the heating chamber 1 and carries a rotary wing 20 secured thereto by means of bolts 19 and 19'. The rotary wing 20 has integral fins 22 and constitutes a field stirrer. A power source 21 for the high-frequency oscillator 10 is installed on the support base.

In operation, high-frequency energy provided by the high-frequency oscillator 10 is guided through the metallic waveguide 7 and the cylindrical passage formed by the coaxial inner and outer conductors 17 and 12 to reach the metallic field beater 20 integral with the lower end of the inner con-

ductor 17, distributed thereby within the heating chamber 1 and absorbed by the matter being heated (not shown).

It will be appreciated that the rotary field stirrer wing 20 made of a metallic material according to the invention provides the function of a kind of antenna, which may be obtained by appropriately adjusting the length of the wing, and promotes the uniform distribution of the energy radiated from the wing in the heating chamber 1 as the wing is rotated. Besides, the uniform energy distribution is further assisted by the fins 22 integral with the wing 20, which stir the energy reflected from the chamber walls of the heating chamber 1.

The rotary wing 20 together with the integral fins 22 might provide truly uniform energy distribution in the heating chamber if the heating chamber were cylindrical. For truly uniform energy distribution in the heating chamber of an other than circular layout, a sort of directivity conforming to the layout of the heating chamber is necessary. The extensions 14 are provided for this purpose, and they constitute an energy distribution modifying means. They are radially spaced in conformity to the layout of the heating chamber 1.

FIGS. 3 to 5 show examples of the arrangement of the energy distribution modifying means 14 conforming to different layouts or shapes of the heating chamber 1. Other arrangements of the energy distribution modifying means in conformity to other different shapes of the heating chamber are of course possible.

The arrangement of the energy distribution modifying means shown in FIG. 3 conforms to the square layout of the heating chamber. The arrangement in FIG. 4 conforms to a rectangular layout, and the arrangement in FIG. 5 to a hexagonal layout. The configuration and dimensions of the energy distribution modifying means may also be determined in conformity to the shape of the heating chamber.

FIGS. 6 to 10 show examples of the energy distribution modifying means 14 provided at or adjacent to the lower end of the outer conductor 12. In the embodiment of FIG. 6, extensions 23 are formed at the lower end of the outer conductor 12 and are spaced such that they correspond to the respective corners or sidewalls of the heating chamber. In the embodiment of FIG. 7, radially extending metal pins 24 are provided, which are similarly located and spaced. In the embodiment of FIG. 8, notches 25 are formed, which are similarly located and spaced. In the embodiment of FIG. 9, portions 26 of an increased wall thickness are formed, which are similarly located and spaced. In the embodiment of FIG. 10, apertures 27 are formed, which are similarly located and spaced. These energy distribution modifying means have the same effect of providing truly uniform energy distribution in the heating chamber.

Other examples of the energy distribution modifying means in respect of configuration and dimensions are also possible in accordance with the invention.

In accordance with the invention the energy distribution modifying means may be provided to either the outer conductor or the inner conductor or to both the inner and outer conductors, in place of providing to the outer conductor as in the foregoing embodiments.

Further, although the field stirrer in the foregoing embodiment is provided to the inner rotary conductor, the same effects may be obtained by providing the field beater to an outer conductor, which is rotary, and which holds the inner conductor stationary.

What is claimed is:

1. A high-frequency apparatus comprising a high-frequency oscillator; a heating chamber for heating substances to be heated by the high-frequency energy produced from said high-frequency oscillator; a first waveguide for guiding the high-frequency energy from said high-frequency oscillator to said heating chamber; a second waveguide connected with said first waveguide, said second waveguide being a coaxial line consisting of a hollow cylindrical outer conductor projecting into the heating chamber and an inner conductor extending through and coaxial with said outer conductor; at least one

stirrer attached to the inner conductor and rotated by a drive shaft provided in the inner conductor; and a part for modifying the energy distribution in the heating chamber uniformly formed on the outer conductor, said part corresponding to the shape of the heating chamber.

2. A high-frequency heating apparatus according to claim 1, wherein said distribution modifying part consists of protuberances formed on the outer conductor, said protuberances corresponding to the respective corners or sidewalls of the heating chamber.

3. A high-frequency heating apparatus according to claim 1, wherein said energy distribution modifying part consists of metal pins provided on the outer conductor, said metal pins corresponding to the respective corners or sidewalls of said heating chamber.

4. A high-frequency heating apparatus according to claim 1,

wherein said energy distribution modifying part consists of notches formed in the outer conductor, said notches corresponding to the respective corners or sidewalls of said heating chamber.

5. A high-frequency heating apparatus according to claim 1, wherein said energy distribution modifying part consists of portions of an increased thickness formed on said outer conductor, said increased thickness portions corresponding to the corners or sidewalls of said heating chamber.

10 6. A high-frequency heating apparatus according to claim 1, wherein said energy distribution modifying part consists of apertures formed in the outer conductor, said apertures corresponding to the respective corners or sidewalls of said heating chamber.
